UNITED STATES PATENT OFFICE

122,455

DESIGN FOR AN INCINERATOR

Harris W. Ayers, Hollywood, Calif.

Application March 19, 1940, Serial No. 91,065

Term of patent 14 years

To all whom it may concern:

Be it known that I, Harris W. Ayers, a citizen of the United States, residing at Hollywood, in the county of Los Angeles and State of California, have invented a new, original, and ornamental Design for Incinerators, of which the following is a specification, reference being had to the accompanying drawing, forming a part thereof.

The figure is a perspective view of an incinerator, showing my new design.

The surface of the rear side of the incinerator is fashioned so as to represent the rough bark of a tree.

I claim:

The ornamental design for an incinerator, as shown and described.

HARRIS W. AYERS.
